UNITED STATES PATENT OFFICE.

ARTHUR W. WELLMAN, OF MADISON, WISCONSIN.

WIRE-FENCE STRETCHER.

SPECIFICATION forming part of Letters Patent No. 788,975, dated May 2, 1905.

Application filed October 8, 1904. Serial No. 227,719.

To all whom it may concern:

Be it known that I, ARTHUR W. WELLMAN, a citizen of the United States, residing at Madison, in the county of Dane, State of Wisconsin, have invented certain new and useful Improvements in Wire-Fence Stretchers, of which the following is a specification, reference being had therein to the accompanying drawings.

This invention relates to a wire - fence stretcher, and particularly to a device adapted for stretching fences composed of woven-wire structures in which it is desirable to stretch the entire body simultaneously.

The invention has for an object to provide a novel construction of stretcher-head adapted to coöperate with a rack-bar and ratchet-lever, so as to secure a step-by-step stretching movement in the oscillation of said lever and to embrace a stretcher-bar by a lateral projection from said head.

Other and further objects and advantages of the invention will be hereinafter set forth and the novel features thereof defined by the appended claims.

5 In the drawings, Figure 1 is a perspective of the invention applied to a fence structure; Fig. 2, a detail perspective of the handle for the ratchet-lever; Fig. 3, a similar view of the stretcher-head in reversed position from Fig. 1; and Fig. 4, a detail vertical section of the ratchet-lever, showing the mounting of the pawls therein.

Like letters of reference refer to like parts in the several figures of the drawings.

5 The letter A designates a stretcher-head of novel construction, which is provided with an aperture A' extending therethrough adapted to receive the ratchet-bar D, having the teeth or notches D' upon the opposite edges thereof, which are adapted to coöperate with pawls C³ and C⁴, pivotally mounted, as at B', at opposite sides of a recess B², extending through the ratchet-lever B. The lower pawl C⁴ is provided with a spring C⁵, surrounding the pivot B', as shown in Fig. 4, to hold it in contact with the bar D, so that when the lever B is pulled forward, as shown by dotted lines in Fig. 1, the lower pawl will automatically engage the next successive notch in the under side of the ratchet-bar. It will be observed

that the upper pawl C³ in the return movement of the lever B will drop by gravity into the next successive notch in the upper side of the ratchet-bar D. The recess B² is provided with oppositely-inclined walls B⁵, converging 55 toward the center to allow a free oscillation of the lever and properly limit the extent thereof. The bar D also extends through this recess. This ratchet is provided on one side with a contact-face b, adapted to bear against 60 a fulcrum-point a, carried upon the face of the head A next adjacent to the lever. Extending laterally from the head A is a shoulder A², adapted to contact with a face of the stretcher-bar C and provided with an arm A³, extended 65 at a right angle to the shoulder A², so as to prevent an outward movement of the bars C from the head, as indicated in Fig. 3.

The ratchet-lever B may be operated in any desired manner—for instance, by means of a 70 removable handle B³, adapted to seat in a socket B' at the upper end of the lever, while the rack-bar D is supported in position and held against the stretching strain by means of a connection to a fixed point—such, for instance, as 75 the chain D², extending to a post or other fixed object D³. The clamping-bars C are composed of two opposite members adapted to be disposed on the opposite sides of the end of 80 a section of wire fencing and clamped in position thereon by any desired means—such, for instance, as bolts C'.

In the operation of the invention it will be seen that the stretcher-head is reversible in 85 position—that is, the shoulder and arm thereon may be disposed either upon the right or left hand side of the stretcher-bars, as the work may require, while the bearing against this head is secured upon the fulcrum-points, so as to avoid any excess of friction, and it 90 allows a free oscillation of the ratchet-lever to secure the step-by-step pushing movement thereof upon the fixed rack-bar. This construction and arrangement of parts provides a simple, efficient, and economically-constructed 95 stretcher adapted for use upon either side of a fence-section and one in which the frictional contact between the head and ratchet-lever is reduced to a minimum.

It will be obvious that changes may be made 100

in the details of construction and configuration without departing from the spirit of the invention as defined by the appended claims.

Having described my invention and set forth 5 its merits, what I claim, and desire to secure by Letters Patent, is—

1. In a fence-stretcher, a rack-bar, a ratchet-lever thereon provided with a contact-face, and a stretcher-head adapted to engage a fence 10 structure and provided with contact-points upon its face next the ratchet-lever to engage the face thereof.

2. In a fence-stretcher, a rack-bar, a ratchet-lever thereon, a stretcher-head adapted to engage 15 a fence structure and provided with contact-points upon its face next the ratchet-lever, and a laterally-disposed shoulder projected from one side of said head.

3. In a fence-stretcher, a rack-bar, a ratchet-lever thereon, a stretcher-head adapted to engage 20 a fence structure and provided with contact-points upon its face next the ratchet-lever, a laterally-disposed shoulder projected from one side of said head, and an arm extended from the side of said shoulder.

4. In a fence-stretcher, a rack-bar, means 25 for securing the same against longitudinal movement, a stretcher-bar secured to a fence, a stretcher-head slidably mounted upon said rack-bar and having a laterally-disposed portion engaging said stretcher-bar, and means carried by the rack-bar for moving said head thereon.

5. In a fence-stretcher, a rack-bar, means 30 for securing the same against longitudinal movement, a stretcher-bar secured to a fence, a stretcher-head slidably mounted upon said rack-bar and having a laterally-disposed portion engaging said stretcher-bar, means car-

ried by the rack-bar for moving said head 4 thereon, a ratchet-lever provided with pawls to engage the opposite faces of said rack-bar and a contact-face at one side thereof, and contact-points upon the face of said head opposite said lever.

6. In a fence-stretcher, a rack-bar having 5 teeth upon its opposite faces, a stretcher-head slidably mounted upon said bar to engage a fence structure and provided with contact-points, a ratchet-lever having a contact-face 10 adapted to slidably engage said contact-points and provided with pivoted pawls at opposite sides of said bar, and a removable handle disposed in a socket at the upper end of said stretcher.

7. In a fence-stretcher, a rack-bar, a ratchet-lever having a recess to receive said bar provided with oppositely-inclined walls converging toward the center and disposed at opposite sides of said bar to form a movable pivotal support therefor upon the bar, and pivoted pawls carried by said lever to engage said bar.

8. In a fence-stretcher, a rack-bar, a ratchet-lever having a recess to receive said bar provided with oppositely-inclined walls converging toward the center and disposed at opposite sides of said bar to form a movable pivotal support therefor upon the bar, pivoted pawls carried by said lever to engage said bar, and a tension-spring surrounding the pivot of one of said pawls and engaging the free end thereof to retain it in contact with the bar.

In testimony whereof I affix my signature in presence of two witnesses.

ARTHUR W. WELLMAN.
